UNITED STATES PATENT OFFICE.

WILLIAM P. BOVARD, OF MANSFIELD, OHIO, ASSIGNOR TO THE OHIO BRASS COMPANY, OF MANSFIELD, OHIO, A CORPORATION OF NEW JERSEY.

ELECTRIC RESISTANCE ELEMENT.

Application filed December 20, 1921. Serial No. 523,735.

To all whom it may concern:

Be it known that I, WILLIAM P. BOVARD, a citizen of the United States of America, residing at Mansfield, in the county of 5 Richland and State of Ohio, have invented certain new and useful Improvements in Electric Resistance Elements, of which the following is a specification.

My invention relates to a resistance element and is particularly adapted for use either singly or in sets combined for different resistances and capacity for the control of electric currents.

My invention resides in the construction, 15 combination and relation of parts more fully disclosed and described hereinafter.

In the accompanying drawings, Fig. 1 is a plan view of my invention.

Fig. 2 is a sectional view on the line 2—2 20 of Fig. 1.

In the preferred form of my construction I employ a frame 1 made preferably of metal. Apertures are provided in the frame to receive the rods 2 as shown. These rods 25 are preferably of metal although they may be made of insulating material if desired. The rods are mounted to project from the frame and are provided with means 3 whereby the rods are secured in place and 30 adjusted with reference to the frame 1.

Upon each rod is mounted a plurality of securing members 4' and 4'' made preferably of vitreous insulating material such as glass, porcelain or fired clay. There may be 35 one or more pairs of these insulating securing members mounted on a rod as required. The members 4' and 4'' are held in position upon the rod by the nuts 5 and the nuts 5 also serve to adjust the position of 40 the members 4' and 4'' upon the rod 2 and to hold the members in clamping engagement with the resistance element 6.

The securing members comprise a pair of interchangeable elements 4' and 4'' provided with a passage to receive the rod 2 and a half groove 7' and 8' located on each side of the passage. Each half groove 7'—8' on one member coacts with counter-part half grooves on the other member to 45 form practically a complete groove to receive the resistance element; that is, half groove 7' coacts with half groove 7'' to form practically a complete groove, which is 50

spaced from the rod 2 thereby holding the resistance element out of contact with the 55 rod 2.

The resistance element 6 is of helically wound wire clamped in the groove 7'—7'' or 8'—8'' or it may be the wire unformed or rods, depending upon the capacity requirements of the element.

To the frame 1 at suitable points are secured terminal members 9—9 provided with nuts 10 for clamping the terminals to the frame and the ends of the resistance element 65 to the terminals. Insulating elements 11 are interposed between the frame and terminals. The nut 12 permits clamping a lead wire to the terminal.

My invention can be used for many purposes where it is desired to mount a resistance in unit form and any number of units may be used together and connected to secure different results as to resistance and current capacity as is well known in the art. 75

I claim:

1. A resistance unit comprising a frame, a rod secured to two opposite sides of the frame, a plurality of clamping members arranged in cooperating pairs mounted on the 80 rod and each pair provided with grooves located on opposite sides of the rod, a resistance element mounted in the grooves and terminal means secured to the frame to receive the ends of the resistance element and 85 conductors to be attached thereto.

2. A resistance unit comprising a frame, a rod adjustably secured to two opposite sides of the frame, a plurality of clamping members arranged in pairs mounted on the 90 rod and each pair provided with grooves located on opposite sides of the rod, a resistance element mounted in the grooves and terminal means secured to the frame to receive the ends of the resistance element and 95 conductors to be attached thereto.

3. A resistance unit comprising a frame, a rod secured to two opposite sides of the frame, a plurality of clamping members arranged in pairs adjustably mounted on each 100 rod and each pair provided with grooves located on opposite sides of the rod, a resistance element mounted in the grooves and terminal means secured to the frame to receive the ends of the resistance element and 105 conductors to be attached thereto,

4. A resistance unit comprising a frame, a rod secured to two opposite sides of the frame, a pair of clamping members mounted on the rod and provided with a groove on each side of the rod to receive a resistance element, a resistance element mounted in the grooves, terminals secured to the frame and having the ends of the resistance elements secured to the terminals.
- 10 5. A resistance unit comprising a frame, a rod secured to two opposite sides of the frame, a pair of clamping members mounted on the rod and provided with a groove on each side of the rod to receive a resistance element, and a resistance element mounted in the grooves.
- 15 6. A support for a resistance element comprising a frame, a rod secured to the frame, a pair of counterpart insulating members mounted on the rod, grooves in the insulating members to receive a resistance element and means to hold the insulating members in clamping relation on the resistance element.
- 20 7. A resistance element support comprising a frame, a rod adjustably secured to the frame, a pair of counterpart insulating members mounted on the rod and disposed on opposite sides of the rod, each half of the insulating member provided with a part-groove on each of the opposite sides of the rod, said part-grooves on the same side of the rod coacting with each other to form a clamping means for a resistance element and means to hold the insulating members in clamping relation on a resistance element.
- 25 8. A resistance unit comprising a frame, a pair of counterpart insulating members mounted on a rod and disposed on opposite sides of the rod and having adjacent faces, a groove formed in the adjacent faces of the insulating members, one on each side of the rod to receive a resistance element, means on the rod for holding the parts of the insulating members in clamping position on the resistance element and in position on the rod and a resistance element mounted in the grooves.
- 30 9. A resistance unit comprising a frame, a rod secured to the frame, a plurality of insulating members in pairs mounted on the rod, each pair of insulating members provided with coacting grooves to receive a resistance element, a resistance element mounted in the grooves and means to hold the insulating elements in position on the rod and in holding engagement with the resistance element.
- 35 10. A resistance unit comprising a frame, a rod secured to the frame, a plurality of insulating members in pairs mounted on the rod, each pair of insulating members provided with a groove to receive a resistance element, a resistance element mounted
- in the grooves and means to hold the insulating elements in engagement with the resistance element.
11. A resistance unit comprising a frame, supporting means secured to the frame, a plurality of pairs of insulating members mounted on the supporting means and free to move longitudinally thereof, means on each pair of insulating members to receive a resistance element, means acting on the end insulating members to hold each pair of insulating members in position upon the rod and a resistance element mounted in the aforesaid receiving means.
12. A resistance unit comprising a supporting frame, supporting means on the frame, an insulating member formed of two parts mounted on the supporting means, means formed in the adjacent faces of the insulating parts and positioned on opposite sides of the supporting means to receive a resistance element, each of said receiving means for the resistance element resting in different planes at right angles to the axis of the supporting means, a resistance element in the receiving means and means to hold the insulating parts in clamping position relative to the resistance element.
13. A resistance unit comprising a supporting frame, a plurality of supporting means secured to the frame, a plurality of pairs of insulating members mounted on each supporting means, each pair of insulating members having adjacent faces with means on the adjacent faces to receive a resistance element, and each supporting means having a pair of insulating members with said receiving means corresponding with receiving means on the other supporting means, a resistance element in the receiving means and means to maintain the insulating members in holding relation upon the resistance element.
14. A resistance unit comprising a supporting frame, a supporting means for insulating members, insulating members mounted in pairs upon the supporting means, means between the insulating members of each pair to receive a resistance element and means to hold the insulating members in clamping relation to the resistance element.
15. A resistance unit comprising a supporting frame, a supporting means for insulating members, insulating members mounted in pairs upon the supporting means, a means between the insulating members of each pair and on opposite sides of the supporting means to receive a resistance element and means to hold the insulating members in clamping relation to the resistance element.
16. A resistance unit comprising a supporting frame, a supporting means for insulating members, insulating members

- mounted in pairs upon the supporting means, a means between the insulating members of each pair and on opposite sides of the supporting means to receive a resistance element and means to hold the insulating members in clamping relation to the resistance element, said means between the insulating members positioned in different planes at right angles to the axis of the supporting means.
17. A support for a resistance element comprising a support member, a plurality of insulating members mounted in pairs upon the support member, means between the insulating members of each pair to receive a resistance element and means to hold the insulating members in position on the support and in holding relation to the resistance element.
18. A support for a resistance element comprising a support member, a plurality of insulating members mounted in pairs upon the support member, means between the insulating members of each pair to receive a resistance element and means to hold the insulating members in position on the support and in holding relation to the resistance element.
19. A resistance unit comprising a supporting frame, a plurality of pairs of supporting means for insulating members, a plurality of insulating members mounted upon each supporting means, means between the insulating members of each pair to receive a resistance element and means to hold the insulating members in position on the supporting means with the corresponding receiving means between the insulating members on each supporting means positioned in substantially the same plane.
- In testimony whereof I affix my signature.

WILLIAM P. BOVARD.
